UNITED STATES PATENT OFFICE.

LOUIS THIEL, OF CINCINNATI, OHIO, ASSIGNOR TO THE CINCINNATI MILLING MACHINE COMPANY, OF CINCINNATI, OHIO, A CORPORATION.

VARIABLE-SPEED MECHANISM.

No. 840,669.

Specification of Letters Patent.

Patented Jan. 8, 1907.

Application filed July 17, 1906. Serial No. 326,610.

To all whom it may concern.

Be it known that I, LOUIS THIEL, a citizen of the United States, residing at Cincinnati, in the county of Hamilton and State of Ohio, have invented certain new and useful Improvements in Variable-Speed Mechanism, of which the following is a specification.

My invention relates to a variable-speed mechanism and box therefor, primarily adapted to be used in connection with machine-tools, such as a milling-machine, but also applicable to other uses employing mechanism of this type.

In machine-tools in particular it is highly desirable that the variable-speed gearing rotate in a practically dust-proof box. To accomplish this result, it is requisite that the actuating mechanism for shifting the movable elements by means of which the changes are accomplished be projected through the walls of the casing without substantially slotting the walls.

The variable-speed mechanism here employed is of the well-known type involving a cone of gear-wheels and a tumbler with its gear-wheels adapted to slide longitudinally and to rock radially relative to the cone, so as to throw into train the driving and driven shafts through the intermeshing of gears of selected ratio. In the specific arrangement of this general cone and tumbler system which I have devised there is one shaft adapted to be rocked to accomplish the sliding movement and another shaft adapted to be rocked to accomplish the swinging movement of the tumbler mechanism.

The features of my invention will be more fully set forth in the description of the accompanying drawings, forming a part of this specification, in which—

Figure 1 is a front elevation of my improved speed-box applied to a milling-machine. Fig. 2 is a side elevation thereof. Fig. 3 is an enlarged section on line *x* *x*, Fig. 2. Fig. 4 is a section on line *w* *w*, Fig. 3. Fig. 5 is a section on line *v* *v*, Fig. 3. Fig. 6 is a section on line *z*, Fig. 3. Fig. 7 is a section on line *a* *a*, Fig. 5. Fig. 8 illustrates the general organization of the shafts and gear-

ing.

1 represents the box inclosing the parts to be hereinafter named.

2 represents the driving-shaft, suitably

journaled in the box and having thereon the driving-wheel 3. (See also Fig. 6.) This wheel 3 is shown as a sprocket-wheel. On this shaft 2 is mounted a sleeve 4, (see Fig. 6,) adapted to turn with and slide on shaft 2, said sleeve being provided with two gear-wheels of different diameter 5 6, respectively.

7 represents a second shaft journaled in the box, which for convenience I will call a "cone-shaft." On shaft 7 is fixed a gear-wheel 8, having an elongated sleeve 9, upon which sleeve are fixed the successive gear-wheels of the cone 10 11 12 13 14, respectively. Also fixed upon shaft 7 is a sleeve 15, having cut thereon the gear-wheels 16 17, and 18 is the gear-wheel fixed on sleeve 15.

The sleeve 4 may be slid so as to engage the gear-wheel 6 with the cone gear-wheel 14 for one rate of drive and so as to intermesh the gear-wheel 5 with the gear-wheel 18 for another change of speed to the cone. To slide sleeve 4, I journal a stud-shaft 19 in the wall of the casing and provide an index-plate 20. Shaft 19 has a crank-handle 21, provided with a detent mechanism 22 to engage the segmentally-arranged orifices 23 of plate 20. On the inner end of shaft 19 is an arm 24, having a fork 25 swiveled in its outer end.

The box 1 is provided with an opening 26, through which this fork 25 projects, the inner end of the fork straddling the gear-wheel 5, so as to shift the sleeve 4 to its different positions.

In order to utilize the shifting of sleeve 4 to give another change of speed to the cone-shaft 7, I provide the stud-shaft 27, upon which are fixed two gear-wheels of different diameter 28 29, respectively, adapted to rotate together. Gear-wheel 28 intermeshes with the pinion 30 on a stud-shaft 31, pinion 30 intermeshing with the gear-wheel 15 on the cone-shaft 7, so that if sleeve 4 be shifted still farther to the left, so as to disengage gear-wheel 5 from gear-wheel 18, gear 5 will be intermeshed with gear-wheel 29, and a third change of speed will be imparted from shaft 2 to the cone-shaft 7.

32 represents a driven shaft journaled in the box, upon which is mounted a tumbler-fork 33, adapted to slide and rock on shaft 32.

34 represents a pinion held by the tumbler mechanism, adapted to turn with and slide on the driven shaft 32. Pinion 34 is inter-

meshed with the gear-wheel 35, fixed upon a stud-shaft 36, journaled in the outer end of the tumbler-forks, as shown in Fig. 4.

As the tumbler mechanism is slid on shaft 32 and rocked thereon, the tumbling gear-wheel 35 may be selectively intermeshed with the gear-wheels 17 8 10 11 12 13 14 of the cone-shaft 7.

The mechanism for rocking the tumbler 33 is shown in Figs. 3, 5, and 7.

37 represents a rock-shaft journaled in the walls of the box 1.

38 represents a sleeve fixed to turn with and slide on rock-shaft 37. Said sleeve 38 is formed with the segmental teeth 39, intermeshing with the segmental teeth 40, formed on the tumbler 33. The tumbler 33 is also provided with an extension 41, formed with an annular groove 42. On sleeve 38 is a segmental collar 44, engaging in the annular groove 42 constantly as the shaft 37 is rocked. Shaft 37 is provided with a handle 45, in the outer end of which is a detent mechanism 46, engaging with the segmentally-arranged orifices 47 on the end portion of the box 1. The positions of these segmental orifices 47 represent the different vertical steps of the cone and the relative position of the tumbling gear-wheel 35 to selectively intermesh with the different-diameter gear-wheels of the cone.

48 represents a rock-shaft journaled in the bottom of the box 1, having an arm 49, carrying on its moving end an engaging plate 50, which engages in the end of the groove 42 of the tumbler mechanism. The front end of rock-shaft 48 is provided with a crank-handle 51, having a detent mechanism 52, engaging with the segmentally-arranged orifice 53 of the index-plate 20. The orifices 53 represent the different lateral positions of adjustment of the tumbler relative to the steps of the cone.

From this description it will be understood that by manipulating the lever 21 three different rates of drive may be imparted to the cone-shaft 7. By manipulating the lever 51 the tumbler mechanism and the segmental rocking mechanism on shaft 37 may be adjusted laterally on shaft 32 and 37 to bring the tumbling gear-wheel 35 laterally opposite any selected gear-wheel of the cone, and then

by manipulating the lever 45 the tumbler mechanism may be rocked to intermesh tumbling gear-wheel 35 with the selected gear-wheel of the cone.

It will thus be seen that I have provided for quite a wide range of changes in a very compact gear-box and that the manipulating-levers for shifting the engaging and disengaging gear-wheels are conveniently arranged so as to operate rock-shafts journaled in the gear-box, and the rock-shafts are connected to the shifting gear elements interior of the box.

Having described my invention, I claim--

1. In a variable-speed device an inclosing box, a cone and tumbler gear-wheel system suitably mounted therein, a rock-shaft journaled in the box, a segmental gear mounted to turn with and slide on the rock-shaft, the tumbler having a segmental gear engaging with the segmental gear of the rock-shaft, a manipulating index-lever for the rock-shaft, a second rock-shaft having connections within the box adapted to slide the tumbler and the segmental gear of the rock-shaft simultaneously, and an indexing-lever for manipulating the second shaft, substantially as described.

2. In a variable-speed device, an inclosing box, a cone and tumbler gear system suitably mounted therein, a driving-shaft also mounted in said box, sliding gears of different diameter on the sliding shaft adapted to be selectively intermeshed with different members of the cone of gears, a rock-shaft and mechanism for sliding the said gears on the sliding shaft, a second rock-shaft journaled in the box, a segmental gear mounted to turn with and slide on the rock-shaft the tumbler having a segmental gear engaging with the segmental gear of the rock-shaft, a manipulating indexing-lever for the second rock-shaft, and a third rock-shaft mounted in the box adapted to slide the said segmental gears in unison, and an indexing-lever for said third rock-shaft, substantially as described.

In testimony whereof I have hereunto set my hand,

LOUIS THIEL.
